UNITED STATES PATENT OFFICE.

HARRY SOSSKIN, OF PHILADELPHIA, PENNSYLVANIA.

RADIATOR.

1,328,752

Specification of Letters Patent. Patented May 4, 1920.

Application filed February 27, 1919. Serial No. 279,633.

To all whom it may concern:

Be it known that I, HARRY SOSSKIN, a citizen of Russia, residing at Philadelphia, in the county of Philadelphia and State of Pennsylvania, have invented certain new and useful Improvements in Radiators, of which the following is a specification.

One object of my invention is to provide a radiator construction which will be particularly well adapted for use in cooling the water used in automobiles for keeping the engine cool.

Another object is to so construct my invention that it can be quickly and easily made and assembled and will be operative to quickly cool the water and thereby prevent the engine or motor from becoming overheated.

Another object is to make my invention in such manner that all of the connected parts will be exposed in such manner that they can be freely and easily soldered at the joints and thereby prevent the radiator from leaking.

These objects, and other advantageous ends which will be described hereinafter, I attain in the following manner, reference being had to the accompanying drawings in which—

Figure 1 is a front elevation of an automobile radiator made in accordance with my invention.

Fig. 2 is an enlarged fragmentary front elevation showing certain of the units of my improved radiator construction connected together.

Fig. 3 is a section taken on the line 3—3 of Fig. 2.

Fig. 4 is an enlarged section taken on the line 4—4 of Fig. 3.

Fig. 5 is a fragmentary perspective view of a portion of my improved radiator, a part of the same being broken away to reveal the internal structure thereof, and

Fig. 6 is a perspective view of a portion of one of the units of my improved radiator construction showing the same before it is soldered.

Referring to the drawings, my improved radiator includes a number of units 7 which are made of continuous strips of sheet metal which are bent to provide a honey comb structure including a number of hexagonal channels or ducts. By being bent in the manner shown in Figs. 2, 4, 5 and 6, each of the units 7 includes two rows of ducts 8

arranged in zig-zag or stepped formation and the sections or bent portions 9 form partitions between the ducts of each row. The portions 10 of each row are soldered together and the portions 11 at their front and rear ends are expanded or bent as shown at 12 so as to extend beyond the intermediate parts 13 which constitute the outer side surfaces of the portions 11. Thus when two of the units 7 are placed side by side as shown in Figs. 2 and 3, the expanded portions 12 will contact with each other and thereby provide a space 14 through which water can pass from the top to the bottom of the units 7. In other words, the spaces 14 provide water passages through which water can pass from the top 15 of the radiator to the bottom 16. The adjacent expanded parts 12 are soldered together both at the front and the rear to prevent leakage of the water passing through the passages 14 and also to connect the units together.

The portions 9 of each of the units 7 have pockets 17 formed therein, said pockets being produced by cuts 18 and pressed portions 19. By cutting and pressing the pockets so that the pressed portions 19 extend toward the rear 20 of the radiator from the cuts 18, I am enabled to provide a taper 85 on each of the pockets so that air passing through the ducts 8 will pass into the openings 21 formed by the cuts 18 and as they engage the tapered or angular surfaces 22 will pass from the ducts of one row into the 90 ducts of the adjacent row of each unit so that said air will be directed transversely to the length of said latter ducts and caused to engage the surfaces of the portions 11 and thereby expedite the cooling of the 95 water passing through said passages 14.

As clearly shown in Figs. 2, 4 and 5, I so make the pockets 17 as to be positioned in a staggered formation within the height of the radiator so that alternate pockets with 100 in said height of the radiator are pressed in opposite directions, so that a portion of the air passing into the front ends of the ducts of each row will be caused to enter the ducts of the immediately adjacent row in the manner above described.

While I have described my invention as taking a particular form, it will be understood that the various parts of my invention may be changed without departing 110 from the spirit thereof, and hence I do not limit myself to the precise construction set

forth, but consider that I am at liberty to make such changes and alterations as fairly come within the scope of the appended claims.

5 Having thus described my invention, what I claim as new and desire to secure by Letters Patent is:—

1. A radiator of the character described including a plurality of units, each of said 10 units consisting of a continuous strip of material having portions bent to provide adjacent rows of ducts, the outer side portions of each of said units at their front and rear ends being offset, whereby when two units 15 are placed together and said units are connected at said projecting parts a passageway will be provided between said units, the engaging portions between said adjacent rows in each unit being in engagement 20 throughout the entire depth of the unit; substantially as described.

2. A radiator of the character described including a plurality of units, each of said 25 units consisting of a continuous strip of material having portions bent to provide adja-

cent rows of ducts, the outer side portions of said units at their front and rear ends projecting beyond the parts between said ends, whereby when two units are placed together and said units are connected at 30 said projecting parts a passageway will be provided between said units, the portions of said strip between adjacent rows in each unit having air deflecting pockets cut and bent to deflect air passing through the ducts 35 of one row into the ducts of the other row, the openings of the pockets being produced by cutting entirely through the portion between the ducts in directions transversely to the length of said ducts and then laterally bulging the portions immediately to the rear of the cutting; substantially as described.

In testimony whereof I have signed my name to this specification in the presence of 40 two subscribing witnesses.

HARRY SOSSKIN.
